FIG. 1.

FIG. 2.

George Louis Rowe INVENTOR

UNITED STATES PATENT OFFICE

90,858

DESIGN FOR AN ADVERTISING LAMP

Guy Landis Rowe, Dallas, Tex.

Application May 8, 1933. Serial No. 48,040

Term of patent 7 years

To all whom it may concern:

Be it known that I, GUY LANDIS ROWE, a citizen of the United States, residing at Dallas, in the county of Dallas and State of Texas, have invented a new, original, and ornamental Design for Advertising Lamps, of which the following is a specification, reference being had to the accompanying drawing, forming part thereof.

Figure 1 is a front perspective view, and
Figure 2 is a rear perspective view.

I claim:

The ornamental design for an advertising lamp
as shown.

GUY LANDIS ROWE.
